UNITED STATES PATENT OFFICE.

WOOLSEY McA. JOHNSON, OF IOLA, KANSAS.

METHOD OF MAKING SULFURIC ACID.

No. 825,057.

Specification of Letters Patent.

Patented July 3, 1906.

Application filed October 10, 1903. Serial No. 176,511.

To all whom it may concern:

Be it known that I, WOOLSEY McA. JOHNSON, a citizen of the United States, residing at Iola, in the county of Allen and State of Kansas, have invented certain new and useful Improvements in Methods of Making Sulfuric Acid, of which the following is a specification.

This invention is a method of making sulfuric acid by electrolytic oxidation of sulfur dioxid or sulfurous acid. It has heretofore been proposed to electrolytically oxidize sulfur dioxid, the gas being injected into the electrolyte through a carbon anode or in proximity to the anode. In such cases the reaction proceeds with separation of sulfur at the cathode, and it has been proposed to keep such separated sulfur from the anode by means of a diaphragm interposed between the electrodes.

According to the preferred embodiment of my invention the sulfur dioxid is oxidized in an electrolytic cell or tank provided with anodes of lead, the electrodes being connected according to the series system—that is to say, in such manner that the intermediate or unconnected plates act as bipolar electrodes. Under these conditions the sulfur dioxid dissolved or otherwise retained in the bath is oxidized at the anodes to sulfuric acid. For the cathode surfaces it is desirable to use a metal having a low cathode potential, whereby the cathodic separation of sulfur is reduced to a minimum. For this purpose copper electrodeposited upon the cathode surfaces is preferred.

My preferred procedure is as follows: Sulfuric-acid solution of about twenty per cent. concentration is saturated with sulfur dioxid by means of a coke-tower or other suitable device. This solution is then caused to flow through the electrolytic cell and past the electrodes therein, whereby the sulfur dioxid is oxidized to sulfuric acid, and a solution is obtained which may approach thirty per cent. concentration. A certain proportion of said acid is withdrawn and concentrated or utilized in any desired manner, while the remaining portion, diluted with water to twenty per cent. and again saturated with sulfur dioxid, is returned to the electrolytic cell, this cycle of operations being repeated indefinitely.

If desired, sulfur dioxid may also be injected into the electrolytic cell, and the tem-

perature of the solution may be lowered to any desired extent to increase the quantity of sulfur dioxid held in solution therein.

For a clear understanding of my invention reference is made to the accompanying drawings, wherein—

Figure 1 is a central longitudinal section of one form of electrolytic cell suitable for the production of sulfuric acid according to my method. Fig. 2 is a plan view of the same, and Fig. 3 is a modification illustrating the use of electrodes whose anode and cathode faces are composed of dissimilar metals.

Referring to Figs. 1 and 2, 1 indicates a tank or containing vessel which may be constructed of cement, lead-lined wood, enameled iron, or other material substantially unaffected by the electrolyte. 2 3 4 represent electrodes disposed transversely of said tank and so arranged therein that the electrolyte is caused to flow alternately over and under the plates. It will be understood that the electrodes may be otherwise arranged in the tank. For instance, lateral passages may be provided between the electrodes and the side of the tank or through the electrodes themselves in such manner as to direct the electrolyte in a tortuous path, or any other suitable arrangement for causing the electrolyte to flow past the active surfaces of the electrodes may be used. The intermediate electrodes 3 have no metallic connection with the circuit and accordingly act as bipolar electrodes, that face of each electrode plate which is nearest the anode acting as a cathode, and the opposite face of each plate acting as an anode, as is well understood. The end electrodes 2 4 are the terminals of the electric circuit. Appropriate inlet and discharge passages 7 8 are provided for the solution.

In the modification illustrated in Fig. 3 the anode connection is assumed to be made at plate 2 and said plate is preferably formed of a sheet of lead. Plate 4, to which the cathode connection is made, may consist of a sheet of copper or of lead faced with copper. The intermediate plates 3, of which any desired number are used, are in this embodiment of my invention formed of sheets of lead 5, having electrodeposited upon their cathode surfaces a layer of metallic copper 6, which, by reason of its low cathode potential in the solution, serves to reduce the quantity of sulfur separated by cathodic reduction. While I consider this to be the preferred form

for the electrodes, I do not limit myself thereto, but may employ anode surfaces of platinum.

In operation, the lead anode surfaces become peroxidized and the sulfur dioxide contained in the electrolyte becomes oxidized to sulfuric acid, said oxidation being probably effected, in part, at least, through the agency of the lead peroxid on the anodes. The injection of sulfur dioxide into the bath, in addition to increasing the concentration of the product, serves to prevent the formation of persulfuric acid. Any traces of sulfur which may be formed are conveniently removed from the solution by boiling to coagulate the sulfur and subsequently filtering.

By the expression "a solution containing sulfur dioxide," as herein employed, I intend to include solutions in which the sulfur dioxide may exist in combination, as solutions of sulfurous acid.

I claim—

1. The herein-described method of producing sulfuric acid, which consists in electrolyzing a solution containing sulfur dioxide by means of electrodes electrically connected in series, the anode faces being composed of lead and the cathode faces of a metal having a low cathode potential, substantially as described.

2. The herein-described method of producing sulfuric acid, which consists in electrolyzing a solution containing sulfur dioxide by means of electrodes electrically connected in series, the anode faces being composed of lead and the cathode faces of copper, substantially as described.

3. The herein-described method of producing sulfuric acid, which consists in electrolyzing a solution containing sulfur dioxide by means of electrodes electrically connected in series, the anode faces being composed of

lead and the cathode faces of electrodeposited copper, substantially as described.

4. The herein - described continuous 45 method of making sulfuric acid, which consists in electrolyzing a solution of sulfuric acid containing sulfur dioxide, thereby increasing the concentration of the sulfuric acid in solution, withdrawing a portion of the 50 solution, diluting the remaining portion, introducing thereinto further quantities of sulfur dioxide, and repeating the electrolysis, substantially as described.

5. The herein - described continuous 55 method of making sulfuric acid, which consists in electrolyzing a solution of sulfuric acid containing sulfur dioxide by means of electrodes electrically connected in series, thereby increasing the concentration of the 60 sulfuric acid in solution, withdrawing a portion of the solution, diluting the remaining portion, introducing thereinto further quantities of sulfur dioxide, and repeating the electrolysis, substantially as described.

6. The herein - described continuous 65 method of making sulfuric acid, which consists in electrolyzing a solution of sulfuric acid containing sulfur dioxide by means of electrodes electrically connected in series, 70 the anode faces being composed of lead and the cathode faces of copper, thereby increasing the concentration of the sulfuric acid in solution, withdrawing a portion of the solution, diluting the remaining portion, introducing thereinto further quantities of sulfur dioxide, and repeating the electrolysis, substantially as described.

In testimony whereof I affix my signature in presence of two witnesses.

WOOLSEY McA. JOHNSON.
